UNITED STATES PATENT OFFICE

156,773

SPINNER TOY

Leonard W. Schaper, West Orange, N. J.

Application March 18, 1949, Serial No. 1,483

Term of patent 14 years

(Cl. D34—15)

To all whom it may concern:

Be it known that I, Leonard W. Schaper, a citizen of the United States of America, residing at West Orange, in the county of Essex and State of New Jersey, have invented a new, original, and ornamental Design for a Spinner Toy, of which the following is a specification, reference being had to the accompanying drawing, forming part thereof.

Figure 1 is a face view of the spinner toy with movable rings showing my new design.

Figure 2 is a plan view of the same.

This application is a continuation in part of my application for Patent Serial Number D. 139,195, filed May 21, 1947.

The dominant features of my new design are shown in solid lines in the drawing.

I claim:

The ornamental design for a spinner toy, as shown and described.

LEONARD W. SCHAPER.
